UNITED STATES PATENT OFFICE.

SAMUEL ROSENTHAL, OF ST. LOUIS, MISSOURI, ASSIGNOR TO NATIONAL COIN CALENDAR CORPORATION, A CORPORATION OF MISSOURI.

SAVINGS BANK.

Application filed April 10, 1922. Serial No. 551,414.

To all whom it may concern:

Be it known that I, SAMUEL ROSENTHAL, a citizen of the United States, residing in the city of St. Louis, State of Missouri, 5 have invented a certain new and useful Improvement in Savings Banks, of which the following is a specification, reference being had to the accompanying drawings, forming a part thereof.

10 This invention relates generally to coin receptacles and, more particularly, to a certain new and useful improvement in coin-receptacles of the type commonly known as savings-banks.

15 The chief object of my present invention is to provide a neat, compact, inexpensive, and readily portable combined savings-bank and calendar adapted especially for distribution by savings institutions and the like 20 to encourage thrift and the saving of money by their customers and depositors, the present bank forming a convenient receptacle for the deposit and accumulation by the customer or depositor of relatively small coins 25 to be subsequently deposited as a lump sum in the savings institution to the credit of the customer or depositor, the opening of the bank for removal of the coins accumulated therein being controlled entirely by 30 the savings institution, and the calendar of the bank being automatically operable upon the insertion of successive coins into the receptacle, to visually remind the customer or depositor to daily deposit, and thereby 35 save a coin in the bank.

With the above and other objects in view, my present invention resides in the novel features of form, construction, arrangement, and combination of parts hereinafter 40 scribed and afterwards pointed out in the claims.

In the accompanying drawings,

Figure 1 is a front elevational view of a 45 combined savings bank and calendar embodying my invention;

Figure 2 is a side elevational view of the bank;

Figure 3 is a front elevational view of the bank with the face or dial cover-plate 50 removed;

Figure 4 is a vertical sectional view of the savings bank on approximately the line 4-4, Figure 3;

Figure 5 is a side elevational view of the

bank with its face or dial cover-plate removed, as indicated by the line 5-5, Figure 3;

Figure 6 is a front elevational view of the savings bank with both the face or dial cover-plate and the calendar dials or disks 60 removed; and

Figure 7 is a fragmental perspective view of the savings bank, showing the locking or separable connection between, and at one end of, the members forming the coin-receptacle proper of the bank.

Referring now more in detail to the said drawings, which illustrate a practical embodiment of my invention and in which like reference characters refer to like parts throughout the several views, the combined bank and calendar has preferably the form or shape best seen in Figure 1 and comprises a casing or a coin receptacle proper of complementing front and rear oppositely disposed marginally flanged sections 1 and 2, respectively, the front section 1 being adapted to removably fit at a portion of its flange 3 within the confines of the flange 4 of the rear section 2, as best seen in Figures 2, 4, and 5. The front section 1 is provided at the upper portion of its flange 3 with a downturned lip 5 and at the lower portion of its flange 3 with a pair of downturned spaced lips 6, 6, which latter lips are adapted to removably fit in slots 7-7 provided in the lower portion of flange 4 of rear section 2 and the upper lip 5 being adapted for releasable engagement by a suitable preferably key-operated latch or lock member 8 90 operably mounted upon rear section 2, as best seen in Figures 2 and 4, for separably or detachably locking the sections 1 and 2 together in coin receptacle-forming relation.

Suitably formed in the flange 3 of front section 1 adjacent the upper end of the bank, as best seen in Figure 2, is a slot 9 through which the coins to be accumulated within the bank may be conveniently inserted.

Disposed relatively flatwise to, and suitably mounted for rotation upon, the front face of section 1, as best seen in Figures 3, 4, and 6, is an upper disk or wheel 10 and a lower disk or wheel 11. Upon its margin, upper disk 10 is provided with ratchet teeth 12, preferably seven in number, and fixed upon disk 10 is a dial 13 bearing upon its

face suitable indicia, such as, for instance, the abbreviations of the names of the days of the week from "Sun." to "Sat." both inclusive, arranged in regular order and 5 spatially related to correspond with the spacing and number of the teeth 12. The lower disk or wheel 11 is relatively larger than upper disk or wheel 10 and is likewise provided upon its margin with an annular 10 series of teeth 14, preferably thirty-one in number; and fixed upon lower disk 11 is a second dial 15 bearing indicia, such as, for instance, the numerals 1 to 31, both inclusive, corresponding to the days of the 15 month, arranged in regular consecutive order and spatially related to correspond with the spacing and number of the teeth 14.

Integral with, or otherwise fixed to, and 20 forming a guide-way longitudinally and somewhat obliquely disposed to the front face of front section 1, are spaced pairs of angle members 16, 16, and disposed for slide- 25 able movement in such guide-way, is an ap- proximately flat bar 17 yieldingly held and retained in lower or so-called normal position, as illustrated in Figure 3, by means of a spring or the like 18. At its upper portion, as best seen in Figures 3 and 6, the 30 front section 1 is longitudinally and obliquely slotted, as at 19, to accommodate a pin or stud 20, projecting rearwardly from bar 17; and pivotally mounted, as at 21, for movement upon the 35 rear face of the front portion of section 1 is a substantially bell-crank lever 22, one arm or portion of which is forked or bifurcated, as at 23, and engages pin 20, as il- 40 lustrated in dotted lines in Figures 3 and 6. The other portion or arm of lever 22 is dis- posed snugly, but movably, in the coin slot 9 and thereby forms substantially a closer 45 for the slot, as best seen in Figure 5.

Pivoted for movement upon the bar 17, 45 are spaced spring-pressed pawls 24 and 25 adapted, when the bar 17 is upwardly ac- tuated as hereinafter more fully appears, for engagement, respectively, with the teeth 12 and 14 of the disks 10 and 11, respectively, 50 for rotarily advancing each of the dials 13 and 15 one tooth or day.

Also disposed relatively flatwise to, and 55 likewise mounted for manual rotation upon, the front face of section 1 approximately intermediate the day and date dials 13 and 15, respectively, is a third wheel 26 carrying a dial 27 bearing upon its face suitable indicia, such as, the abbreviations of the names of the months of the year from 60 "Jan." to "Dec." both inclusive, arranged in suitably spaced consecutive order.

Enclosing the front section 1 of the coin- 65 receptacle proper, and the several dials 13, 15, and 27, and the operating means therefor mounted upon said front section 1 and en-

gaging the forward edge of the rear section 2 of the coin-receptacle, as best seen in Figure 2, is a third or so-called cover section 28, formed or provided with suitable sight apertures or openings 29, through which a 70 particular day, date and month of the dials 12, 15 and 27 are visible, as illustrated in Figure 1.

In use and practice, the present bank is 75 designed especially, as I have before mentioned, for use by savings institutions to encourage thrift and the saving of money by its customers or depositors. To such end, the bank is loaned or given the customer, the key for actuating the lock 8, to enable with- 80 drawal of the accumulated coins, being re- tained by an official of the institution. The bank being so in use by a customer, it will be evident that, as a coin is inserted into slot 85 9, the coin will engage with the slot-closing portion of the lever 22, the lever 22 thereby pivotally actuated, the bar 17, through the engagement of the bifurcated portion of lever 22 with said pin 20, yieldingly moved upwardly or into the position thereof illus- 90 trated in Figure 6, and the day and date dials 13 and 15, through engagement there- 95 with by the pawls 24 and 25, as also illus- trated in Figure 6, rotarily advanced one day, as I have before described, the coin, in turn, falling into the coin-receptacle and the lever 22 and bar 17, with its pawls 24 and 25, returning under the pull or tension of spring 18 to normal position. The day and date dials 13 and 15 are thus automatic- 100 ally and successively actuated in unison on each deposit of a coin within the receptacle and serve, in order that they may agree and exhibit the proper day and date, to effective- 105 ly remind the customer to make the required "saving" each day.

At the end of the month, the bank is de- 110 livered by the customer to the particular savings institution, sections 1 and 2 forming the coin-receptacle disconnected or unlocked, the accumulated coins deposited in a lump sum in the institution to the credit of the customer, the face or cover section 28 re- 115 moved from about the dial carrying section 1, the day and date dials 13 and 15, as well as the month dial 27, manually reset, as re- 120 quired, to again exhibit the proper day, date, and month, the coin-receptacle forming sec- 125 tions 1 and 2 replaced and relocked, the sec- tion 28 also replaced in dial covering posi- 130 tion upon section 1, and the bank again given to the customer for repeated use.

As best seen in Figures 3 and 6, a spring 30 is suitably mounted upon the front sec- 125 tion 1 to engage the teeth 14 of disk 11 to yieldingly hold the dials 13 and 15 and the bar 17 against actuation without the actual deposit of a coin within the receptacle; and a short partition 31 is preferably fixed with- 130 in the coin-receptacle section 1, as best seen in

Figure 5, to prevent interference with the successive operations of lever 22 by the coins accumulated within the receptacle.

My new bank is preferably of such relatively small size and dimension as to conveniently fit in a coat pocket, and is thus readily portable by the customer to and from the savings institution. The bank is neat and compact in appearance, and thus, in addition to efficiently and positively performing its function of a savings and thrift habit-creating bank, provides a useful and attractive ornamental calendar for a desk, table, or the like.

It will, of course, be understood that my new bank may be made or constructed for receiving and actuation by, coins of different denominations, each particular bank being designed for use with, and actuation by, coins of like denomination, and that changes in the form, construction, arrangement, and combination of the several parts of the bank may be made and substituted for those herein shown and described without departing from the nature and principle of my invention.

Having thus described my invention, what I claim and desire to secure by Letters Patent is:

1. A savings-bank comprising a casing having a coin-slot and an elongated pin-slot, in combination with a dial mounted for rotation upon the casing, and means for rotarily actuating the dial upon the insertion of a coin into the casing through the

coin-slot, said means including a bar 40
slidable upon the outer surface of the casing, a pin on the bar projecting through the pin-slot, a pawl mounted upon the bar adapted for actuating engagement with the dial, and a bell-crank lever pivoted for oscillation upon the under surface of the casing and having one slotted arm in constant bar actuating engagement 45
with said pin, the other arm being disposed adjacent said coin-slot for actuating engagement by the inserted coin.

2. A savings-bank comprising a casing having a coin-slot and an elongated pin-slot, 50
in combination with a dial mounted for rotation upon the casing, means for rotarily actuating the dial upon the insertion of a coin into the casing through the coin-slot, said means including a bar 55
slidable upon the outer surface of the casing, a pin on the bar projecting through the pin-slot, a pawl mounted upon the bar adapted for actuating engagement with the dial, and a bell-crank lever pivoted for oscillation 60
upon the under surface of the casing and having one slotted arm in constant bar actuating engagement with said pin, the other arm being disposed adjacent said coin-slot 65
for actuating engagement by the inserted coin, and means having engagement with the dial for yieldingly holding the dial against rotation.

In testimony whereof, I have signed my name to this specification.

SAMUEL ROSENTHAL.
